UNITED STATES PATENT OFFICE.

LEVI S. GARDNER, OF DETROIT, MICHIGAN.

CARBURETER.

1,299,454.

Specification of Letters Patent. Patented Apr. 8, 1919.

Application filed February 15, 1917. Serial No. 148,722.

To all whom it may concern:

Be it known that I, LEVI S. GARDNER, a citizen of the United States, residing at Detroit, county of Wayne, State of Michigan, 5 have invented a certain new and useful Improvement in Carbureters, and declare the following to be a full, clear, and exact description of the same, such as will enable others skilled in the art to which it pertains 10 to make and use the same, reference being had to the accompanying drawings, which form a part of this specification.

My invention has for its object to produce a simple and novel carbureter which, without 15 additional attachments or appliances, will enable the carbureter to take its supply of fuel from a storage tank or reservoir located either below or above a horizontal plane passing through the carbureter.

20 A further object of my invention is to produce a carbureter having a simple and novel structural arrangement.

Briefly stated, my invention, viewed in one of its aspects, consists in utilizing the 25 suction of the engine on the carbureter in such a way that a partial vacuum is maintained in the float chamber or corresponding element of the carbureter, which vacuum will be sufficient to cause an upward flow of 30 liquid fuel from the main fuel tank, even though the latter be placed at a considerable distance below the level of the carbureter; thus doing away with auxiliary reservoirs into which it has heretofore been believed 35 necessary to lift the fuel from low lying tanks so as to permit a gravity feed to the carbureter. Not only does my improved method of securing a feed of fuel to the carbureter simplify and reduce the number of 40 elements forming part of the power plant, but it is also much more efficient and requires the expenditure of less energy than do the old systems, because in the latter the fuel must be raised above the level of the 45 carbureter in order that it may flow by gravity to the carbureter, while in my arrangement the lift from the main tank or reservoir is only to the level of the carbureter. It often happens in connection with 50 vacuum feed systems of the type to which I have heretofore referred as being in use, that at high speeds there is not a sufficient vacuum in the engine manifold to cause the auxiliary reservoir to be supplied from the main 55 reservoir as fast as the carbureter is taking

fuel from the auxiliary reservoir; and consequently the auxiliary tank will sometimes become drained at high speeds and the engine will fail to receive the proper supply of fuel. By eliminating the extra lift, necessary to bring the fuel into an auxiliary reservoir at a higher level than the carbureter, and lifting the fuel simply to the level of the carbureter, an effective feed can be maintained at much higher speeds, that is with 60 a smaller vacuum in the manifold, than is possible with the old systems.

The various features of novelty whereby my invention is characterized will herein-after be pointed out with particularity in 70 the claims; but, for a full understanding of my invention and of its objects and advantages, reference may be had to the following detailed description taken in connection with the accompanying drawings, wherein:

Fig. 1 is a horizontal section taken through a carbureter arranged in accordance with my invention, the section being taken approximately at the axis of the main air passage;

Fig. 2 is a vertical section taken approximately on line 2—2 of Fig. 1;

Fig. 3 is a section taken approximately on line 3—3 of Fig. 1;

Fig. 4 is a view on the same plane as Fig. 80 2, of a fragment of the carbureter, showing the main throttle valve in a different position from that which it occupies in Fig. 1;

Fig. 5 is a side elevation of the throttle valve; and

Fig. 6 is a view similar to Fig. 2, except that the float chamber is shown partly in elevation, illustrating the same carbureter equipped with a butterfly choke valve.

In the drawings I have illustrated my invention in only a single form with one slight modification and, for the sake of brevity, I shall confine the detailed description to this particular form; but I desire to have it understood that my invention, in its broader aspects, may take a great variety of forms.

Referring to the drawings, 1 represents the tubular body of a carbureter open at one end as at 2 to receive the main supply of air and open at the other end as at 3 for the purpose of delivering the carbureted air to the engine. Below the member 1 is the fuel reservoir or float chamber, 4. In addition to suitable means for supplying fuel from the chamber 4 into the tubular member 105 110

1, there is also an air passage leading from a point above the normal liquid level in the chamber 4 to a point within the interior of the tubular body member. In the construction illustrated, this passage is indicated at 5. With this arrangement, whenever the engine is running so that fuel is being drawn out of the fuel chamber in the carburetor, air is being drawn out of the space within 10 this chamber above the fuel level and a partial vacuum is thus produced in the fuel chamber. Such a vacuum will of course permit fuel from the main reservoir to be forced upwardly into the carburetor by atmospheric pressure on the fuel in the main reservoir. If nothing else were done, however, than to provide the air passage, the effect would be to produce substantial equilibrium in subatmospheric pressure above 15 the fuel in the chamber and at the fuel outlet, so that the flow of fuel from the chamber would theoretically be impossible and in practice, such flow as there might be would be uncertain and erratic. I have therefore 20 provided means for limiting the degree of vacuum that can be established and maintained in the fuel chamber above the fuel level so that when the engine is running a predetermined substantial partial vacuum 25 will be maintained above the fuel while a greater variable partial vacuum will be maintained at the fuel outlet into the carbureting or mixing chamber, depending upon the speed of the engine. This I accomplish 30 by providing the chamber 4 with a port leading to outside atmosphere and controlling the port by an inwardly opening check valve. In the arrangement illustrated, this air port is indicated at 6 and is controlled 35 by a gravity valve, 7, vertically slideable in a housing or casing, 8, formed in the body of the carburetor in proximity to the upper end of the fuel chamber. The port 6 enters the bottom of the housing 8 and the 40 valve 7 is inserted through the top of the housing which is then closed in any suitable way as, for example, by a screw plug 9. It will be seen that by varying the weight of the valve 7 or the size of the port 6 or both 45 of them, the degree of vacuum which must be established in the fuel chamber above the fuel therein, before the valve will lift, may be varied within wide limits and, after the adjustments have once been made, will 50 thereafter remain constant.

The fuel is delivered from the chamber 4 through a vertical passage 10, extending vertically through a post 11 which projects downwardly from the body of the carburetor; the post 11 being at the axis of the fuel chamber and serving as a support for the bowl 12. The passage 10 is open at both ends so that while its upper end communicates with the main air passage in the body 55 of the carburetor, its lower end communi-

cates with atmosphere. Fuel is allowed to flow into the passage 10 through suitable ports, 13 and 14, the former being controlled by a thermostat 15. Of course the fuel may be led in any suitable way into the passage 70 10 from a point within the fuel chamber below the normal liquid level. The lower end of the passage 10 is controlled by a suitable inwardly opening check valve which will shut off communication with the outside air 75 when the engine is not running and will thus permit the passage 10 to serve as a well which will fill up with fuel when the engine is shut down, but will lift and allow outside air to flow upwardly through the 80 passage, pick up fuel, and enter the main air passage of the carburetor to mingle with the main air supply. In the arrangement shown, the lower end of the air passage is reduced in diameter as indicated at 16, the 85 part 16 being formed in a plug, 17, which serves also as a nut to hold the bowl 12 in place. The upper end of the plug 17 thus forms a valve seat with which the check valve co-operates. This check valve, like the 90 valve 7, may consist of a simple gravity member, 18, tending constantly to rest upon the valve seat at the upper end of the member 17. The parts are so proportioned that the valve 18 will not rise from its seat until 95 the vacuum in the passage 10 is greater than the vacuum which must be established in the fuel chamber above the fuel level in order to cause the valve 7 to rise; thus insuring that whenever the engine is running there will 100 always be a greater vacuum in the passage 10 than above the fuel in the fuel chamber. It therefore follows that whenever the engine is running, the partial vacuum produced in the fuel chamber does not prevent a 105 proper flow of fuel into the passage 10, because there will be a differential pressure on the fuel in the direction to force it into the passage 10 by reason of the higher or greater vacuum in this passage than in the 110 fuel chamber. On the other hand, after an adequate vacuum in the fuel chamber has been produced, the air valve 18 will rise, so that the fuel will be taken up by a stream of air and be carried into the carbureting or 115 mixing chamber in the form of a rich mixture. In the arrangement shown, fuel is delivered to the chamber 4 through a port, 19, controlled by a float-controlled valve, 20.

Another novel feature of the carburetor 120 illustrated, which may be used in conjunction with the vacuum feature or independently thereof is the main valve for controlling the flow of both the main air supply and the rich gaseous mixture delivered 125 from the passage 10. Extending vertically across the interior of the body of the carburetor and forming a plug or valve therefor is a cylindrical shell, 21, co-axial with the fuel passage 10. The member 21 is closed 130

at its upper end and projects out through the top of the body casting where it is provided with an actuating lever or arm, 22. The shell or casing is open at the bottom and it is of such a diameter or is so located that the port 5 leading from the fuel chamber opens into the interior thereof. A tunnel, 23, extends transversely through the shell 21, the ends of the tunnel being open and the walls being imperforate so that there is no direct communication between the interior of the tunnel and the space within the interior of the shell surrounding the tunnel. The tunnel is preferably made smaller at one end than at the other, the larger end being the inlet end and the smaller end the outlet end. When the shell is so placed that the axis of the tunnel lies at right angles to the axis of the body of the carburetor, the shell 21 serves as a valve to prevent air from being taken in through the inlet end 2. When the shell is turned from the aforesaid position, a passage from the inlet end to the outlet end of the carburetor is provided, the size of the passage depending upon the angular position of the shell.

The wall of the shell is provided with a series of small openings, 24, arranged in a circle in proximity to the wall of the tunnel at the small end of the latter; the perforations, 24, being preferably inclined so that continuations thereof would converge at a point beyond the small end of and at the axis of the tunnel.

It will be seen that when the main valve 21 is in such a position that air can pass from the inlet end 2 through the carburetor, a suction will be produced which will cause air or a mixture of air and gas to be drawn out through the ports or perforations, 24, and be effectually mixed with the main air supply; air coming up through the port 5 and a rich mixture of air and gas coming up through the passage 10.

The ports or perforations 24 do not extend entirely around the mouth of the tunnel because when the main valve is in its closed position in which no air can flow through the tunnel, none of the ports or perforations 24 should be exposed. As the valve is shifted to open it a little, one or two of the ports 24 are uncovered so that the requisite amount of fuel may be delivered. Then, as the valve is opened wider and wider, allowing more and more air to enter, additional fuel supplying ports are uncovered.

In starting the engine it is desirable that a rich priming charge be provided, which necessitates shutting off the main supply of air. In the drawings I have illustrated two means by which a priming charge may be obtained, and either means must be used alone or in conjunction with the other. Thus, as shown in Fig. 1, there is a port, 25,

extending through the shell 21 near the large end of the tunnel, the angular distance of this port from the small end of the tunnel being slightly greater than the angle through which the valve must be turned to bring it from full open to full closed position. Therefore, by continuing the turning movement of the valve slightly past its closed position, the port 25 will be uncovered on the outlet side of the carburetor and, upon starting the engine, the charge contained in the passage 10 will be drawn up through the valve 21 in the port 25, together with air entering the lower end of the passage 10. The same result may be obtained by providing a shut-off valve such as the butterfly valve, 26, illustrated in Fig. 6, this valve being placed in the inlet end of the carburetor in advance of the main valve. In starting the engine the valve 26 may be closed so as to shut off the entrance of outside air through the inlet end 2, while the valve 21 is allowed to remain in its open position with the ports or perforations 24 uncovered. The priming charge in this instance will be drawn through the ports or perforations 24 instead of through an auxiliary port.

I claim:

1. A carburetor having a main air passage, a hollow valve extending across said air passage and having a tunnel extending therethrough for the passage of the main charge of air, a source of fuel supply communicating with the interior of said hollow valve, and there being a series of ports extending through the wall of said valve in proximity to one end of said tunnel.

2. A carburetor having a main air passage, a hollow valve extending across said air passage and having a tunnel extending therethrough for the passage of the main charge of air, a chamber for liquid fuel communicating with the interior of the hollow valve by means of a passage opening into the chamber at a point above the liquid level and by another passage opening into the chamber at a point below the liquid level, means controlled by an inwardly opening check valve for admitting air into said chamber above the liquid therein, and said hollow valve having one or more ports extending through the wall thereof in the vicinity of one end of said tunnel.

3. In a carburetor, a body member containing a main air passage open at both ends and having its axis horizontal, a post projecting downwardly from said body member, a fuel chamber surrounding said post, there being a passage in said post communicating at its upper end with the main air passage, there being a port leading from a point in the interior of the fuel chamber below the liquid level therein to a point in said passage in the post lying below said liquid level, and

- there being also an air inlet in the lower end of the passage in the post, and a check valve located in the fuel passage and controlling said air inlet.
5. 4. In a carbureter, a body member containing a main air passage open at both ends and having its axis horizontal, a post projecting downwardly from said body member, a fuel chamber surrounding said post, there being a passage in said post communicating at its upper end with the main air passage, there being a port leading from a point in the interior of the fuel chamber below the liquid level therein to a point in said passage 10 in the post lying below said liquid level, and there being also an air inlet communicating with the passage in the post at a point below the discharge end of said port, and a check valve located in the fuel passage and controlling said air inlet.
5. In a carbureter, a body member containing a main air passage open at both ends, a post projecting downwardly from said body member, a fuel chamber surrounding said post, there being a passage in said post communicating at its upper end with the main air passage, there being a port communicating with the interior of the fuel chamber at a point below the liquid level 15 therein and opening into the passage in the post at a point below said level, and there being also a passage leading into said main air passage from the top of said chamber, said chamber having an air inlet, a check valve located in the fuel passage and controlling said air inlet, and means including an inwardly-opening check valve for admit- 20 ting atmospheric air into the passage in said post.
6. A carbureter having a main air passage 40 and a well opening at its upper end into the aforesaid passage, a fuel chamber having a restricted delivery outlet into said well, there being a port leading from said well to atmosphere at a point below said delivery outlet, 45 and an inwardly opening check valve located in said well and controlling said port.
7. A carbureter having a main air passage, a hollow valve extending across said air passage and having a tunnel extending therethrough for the supply of the main charge of air, a well opening at its upper end into the interior of said hollow valve, means for delivering liquid fuel into said well, and there being a plurality of ports extending through 50 the wall of said valve in proximity to one end of said tunnel.
8. A carbureter having a main air passage, a hollow valve extending across said air passage and having a tunnel extending therethrough for the supply of the main charge of air, a well opening at its upper end into the interior of said hollow valve, means for delivering liquid fuel into said well, there being a plurality of ports extending through the wall 55 of said valve in proximity to one end of said tunnel, and means for permitting air to flow upwardly through said well and into the main air passage when the engine to which the carbureter is connected is running. 60
- In testimony whereof I sign this specification.

LEVI S. GARDNER.
